Henry B. Evert,
ATTORNEY.

UNITED STATES PATENT OFFICE.

ALEXANDER F. HUMPHREY, OF ALLEGHENY, PENNSYLVANIA.

TROLLEY-WHEEL.

SPECIFICATION forming part of Letters Patent No. 605,716, dated June 14, 1898.

Application filed December 9, 1897. Serial No. 661,262. (No model.)

To all whom it may concern:

Be it known that I, ALEXANDER F. HUMPHREY, a citizen of the United States of America, residing at Allegheny, in the county of 5 Allegheny and State of Pennsylvania, have invented certain new and useful Improvements in Trolley-Wheels, of which the following is a specification, reference being had therein to the accompanying drawings.

10 This invention relates to certain new and useful improvements in trolleys, and has for its object to construct a trolley which when placed in position on the wire will be prevented from accidental displacement therefrom.

15 The principal features of my invention reside in the two spring-actuated arms which extend over the trolley-wheel and prevent the wheel from leaving the wire, together with 20 novel means for retracting these arms to permit the removal of the wheel from the wire when it is so desired, and in the novel construction whereby the trolley is permitted to pass safely over the switch arranged at the 25 crossing of two lines of current-wires.

25 The invention finally consists in the novel construction, combination, and arrangement of parts to be hereinafter more specifically described, and particularly pointed out in the 30 claim.

35 In describing the invention in detail reference is had to the accompanying drawings, forming a part of this specification, and wherein like letters of reference indicate similar parts throughout the several views, in which—

Figure 1 is a perspective view of my improved trolley, together with a similar view of a switch provided at the two crossing lines. Fig. 2 is a rear elevation of the trolley. Fig. 3 is a side view of the same. Fig. 4 is a side view of a portion of the fork, showing the inclined face of one of the jaws within which the spring-actuated arms are pivoted.

40 Referring now to the drawings by reference-letters, *a* indicates the fork, which is formed on or rigidly secured to a suitable ferrule *b*, that is attached to the upper end of the trolley-pole *c*. Within the two prongs forming the fork is journaled the axle or shaft *d*, on 45 which is mounted a suitable trolley-wheel *e*, said shaft having arranged thereon between the inner face of the prongs and the sides of

the trolley-wheel coil-springs *f*, which retain the trolley-wheel normally on the center of the shaft, but permit of its lateral movement 55 within the fork. The upper ends of the prongs forming the fork are formed into frames *a'*, extending rearwardly and forwardly of the said prongs. The forward extensions of said prongs are provided with jaws *a²*, in which 60 are pivotally secured the arms *b'*, which extend inwardly between the two prongs and carry small rollers or wheels *b²* in their inner ends, which engage each other and close the opening through which the wire is passed 65 when placing the trolley in position thereon. These arms are held in the closed position by means of stiff coil-springs *c'*, attached to the rear face of the same and to the inner face of the rearwardly-extending portion of the 70 frame *a'*.

For the purpose of guiding the trolley under a switch provided at crossings I have formed cut-away portions or recesses *d'* in the rearwardly-extending portions of the frame 75 *a'* and have journaled to the said portions within these recesses a small roller or wheel *d²*, which projects slightly above the edge of the frame *a'*. The switch or crossing *g* provided at the intersection of the two lines is 80 passed by arranging wings *h* on the upper face of the wire, which come in contact with the rollers *b²* and open the arms *b'* previous to their reaching the switch *g*, while at the same time a wing *h'*, having an inclined face 85 *h²* and which is arranged on the underneath side of the wire, engages upon the trolley-wheel, so as to depress the same and permit the trolley to ride in under the switch *g*, where it is assisted in its movement by means of the 90 small wheels or rollers *d²*. This construction may of course be varied, and I do not wish to limit myself to that shown herein, as this illustration is given merely for the purpose of showing how the trolley may be passed under 95 the switch, as the main invention resides in the trolley.

For the purpose of placing the trolley upon the wire the controlling-line *k* may be divided or formed into branches *k'* at its upper end, 100 which are passed through suitable keepers *k²*, provided therefor on the inner face of the prongs *a*, and then attached near the free ends of the arms *b²*. Thus when the cord is pulled

downward the same retracts the arms b^2 and permits the trolley-wheel e to pass into or out of engagement with the wire, as the case may be. It will also be noted that various changes 5 may be made in the details of construction without departing from the general spirit of my invention.

Having fully described my invention, what I claim as new, and desire to secure by Letters 10 Patent, is—

A trolley comprising a fork with a shaft mounted therein, a trolley-wheel mounted on said shaft, springs arranged on said shaft and adapted to retain said trolley-wheel in a central position thereon, arms pivotally secured 15 in the upper ends of said fork and having

coiled springs attached to their rear faces thereby preventing the wheel from leaving the wire, rollers mounted on the upper ends of said fork and extending above the same, 20 said rollers assisting the trolley in passing switches arranged on the wire, and means whereby said arms can be operated to pass the trolley-wheel into or out of engagement with the wire, substantially as herein shown and 25 described.

In testimony whereof I affix my signature in presence of two witnesses.

ALEXANDER F. HUMPHREY.
